US0D1039839S

(12) **United States Design Patent** (10) **Patent No.:** **US D1,039,839 S**
(45) **Date of Patent:** **** Aug. 27, 2024**

(54) **EARPHONE BOX**

(71) Applicant: **BEIJING XIAOMI MOBILE SOFTWARE CO., LTD.**, Beijing (CN)

(72) Inventor: **Yuhao Zhang**, Beijing (CN)

(73) Assignee: **Beijing Xiaomi Mobile Software Co., Ltd.**, Beijing (CN)

(**) Term: **15 Years**

(21) Appl. No.: **35/516,073**

(22) Filed: **Jan. 26, 2022**

(80) **Hague Agreement Data**

Int. Filing Date: **Jan. 26, 2022**

Int. Reg. No.: **DM/219858**

Int. Reg. Date: **Jan. 26, 2022**

Int. Reg. Pub. Date: **Jan. 27, 2023**

(30) **Foreign Application Priority Data**

(57) **CLAIM**

The ornamental design for an earphone box, as shown and described.

DESCRIPTION

1. Earphone box

1.1 : Front

1.2 : Back

1.3 : Left

1.4 : Right

1.5 : Top

1.6 : Bottom

1.7 : Perspective

Reproductions 1.1-1.7 show the earphone box. The product is used for accommodating and charging earphones. Broken lines shown in reproductions indicate portions of the earphone box that form no part of the claimed design.

1 Claim, 7 Drawing Sheets
